METHOD OF MANUFACTURING STAPLE FIBER

Erhard Witte, Berlin-Lichterfelde, Germany, assignor to North American Rayon Corporation, New York, N. Y., a corporation of Delaware

Application June 27, 1935, Serial No. 28,679
In Germany July 3, 1934

9 Claims. (Cl. 18—54)

The present invention relates to the manufacture of artificial silk filaments from a cellulosic spinning solution, but primarily has for its object the production of staple fiber in a continuous operation.

It has heretofore been the practice to produce staple fiber from artificial silk by first twisting a large number of freshly spun threads into a rope-like hank and then winding it upon reels in order to be subjected to the usual after-treatment. Since these rope-like hanks possess a tensile strength of 10,000 denier or more, it is obvious that the hanks require strong and costly machinery.

In accordance with another well-known method, the cutting of the single threads is carried out immediately upon spinning of the same, and the short pieces of thread are then subjected to the usual after-treatment. It has also been proposed to intermittently stop the extrusion of the spinning solution through the spinnerettes in order to produce short pieces of thread. The after-treatment of these short pieces of thread, however, require many manipulations which increase the cost of production.

Still another method of producing staple fiber which has been proposed is the spinning of threads into spinning pots. The latter are rotated at high speeds, thereby extracting the moisture from the yarn. Also this process is very costly due to the manual labor required in order to obtain the finished product.

It is therefore one object of the present invention to produce staple fiber from artificial silk spinning solutions in a continuous operation without employing separate winding or reeling operations.

Another object of the present invention is the employment of an intermediate treatment of the undivided thread with a diluted soda solution.

Still another object is the control of the drying process which is carried out in two stages.

These and other objects of the present invention will become more apparent from a study of the following description and by reference to the attached drawings, wherein:

Fig. I is a top or plan view of the entire machine;

Fig. II is a vertical longitudinal view of Fig. I; Figs. III and IV are enlarged detail vertical sectional views disclosing modified constructions of drying plates or drying rollers through which the thread bundle may be passed.

Referring now more particularly to the drawings in which like numerals indicate like parts, the new device comprises two troughs 1 and 2 arranged at rectangular position with respect to each other. These troughs are divided into a number of spinning grooves 4 through the par-

titions 3. Each of these spinning grooves contains a spinning pipe provided with a spinnerette through which artificial filaments having 1000 denier each are extruded into the spinning bath. The spinning pipes, spinnerettes and artificial threads within the troughs are not shown in the drawings. After leaving the spinning bath the threads 5 are grouped together by means of thread guides 6, 7 and 8 from the trough 1, and 9, 10 and 11 from the trough 2, and then united into thread bundles 14 and 15 through the thread guides 12 and 13, respectively. These thread bundles 14 and 15 are passed over freely rotating rollers 16 and 17 and then led to the actual take-up roller 19 by means of the thread guide 18. The take-up roller 19 is positively driven by the shaft 20 and gear wheels 53; the circumferential speed of the take-up roller 19 is approximately 60 meters per minute.

As shown in Fig. II, the thread bundle 21 united by the thread guide 18 and drawn off by the take-up roller 19 is led to the roller 22 rotating at the same circumferential speed as the roller 19 and driven by gear 54, and is then passed to the positively driven roller 23 which rotates at a peripheral speed of only 58 meters per minute and is driven by gear 55. Between the rollers 22 and 23 the thread bundle 21 rises vertically and is washed with warm water of approximately 30-40° C. supplied by the spray nozzle 24; the flow of the water being countercurrent to the direction of travel of the thread bundle. The major portion of the precipitating bath adhering to the thread bundle will thus be removed and is collected in the receiver 25 in order to be used again if desired. From the roller 23 the thread bundle is led to the roller 28 by way of freely rotating guide rollers 26 and 27. The roller 28 rotates at the same peripheral speed as the roller 22 and is driven by gear 56, thus effecting a tension of the thread bundle between the rollers 23 and 28. This up and down passage of the thread bundle 21 is repeated a plurality of times. The upward movement is carried out without tension while during the downward movement a tension is imparted to the thread bundle. During this passage the peripheral speed of the rollers 30, 32, 34 and 36 driven by gears 57, 58, 59 and 60, respectively, is approximately 60 meters per minute while that of the rollers 29, 31, 33, 35 and 37 driven by gears 61, 62, 63, 64 and 65, respectively, is approximately 58 meters per minute. During the upward movement of the thread bundle, i. e., when no tension is imparted thereto, the thread bundle is subjected to a wet-treatment by means of the spray nozzles 38, 39, 40, 41 and 42.

The spray nozzles 38, 39 and 40 are provided for the washing of the thread bundle with water, and the spray nozzle 41 for the intermediate washing with a diluted soda solution (approxi-

mately 0.5% solution), in order to remove any residues of acid which might still be contained in the thread bundle. In order to remove the soda solution from the thread bundle, an additional treatment with water through the spray nozzle 42 is provided. From the roller 37 the thread bundle is passed over freely movable guiding devices 43 to a drying cylinder 44, whereby the rollers 45, 46, 47 and 48 press the thread bundle onto the drying cylinder 44 in order to facilitate its guidance. The drying cylinder 44 which rotates at a circumferential speed of approximately 60 meters per minute reduces the moisture content of the thread bundle to about from 30 to 15 50%. After passing the drying cylinder 44 the thread bundle is led through grooved drying plates 49 and 50 which by means of belt-conveyors rotate in the direction of travel of the thread bundle. During the passage through the 20 grooved drying plates the thread bundle obtains a corresponding curling and is at the same time completely dried. The thread bundle is then led to the cutting device 51. By means of well-known rotating cutters the thread bundle is cut 25 into the desired staple length and then drops into the receiver 52.

Two modifications of the drying plates 49 and 50 are shown in Figures III and IV. In accordance with Fig. III the drying plates are so constructed that the grooves of the upper plate 61 engage with the elevations of the lower plate 66, and vice versa. In accordance with Fig. IV rods 68 arranged closely together are provided instead of grooved drying plates. It is advisable to construct these rods freely rotatable; they form a kind of a grate through which the thread bundle passes in a wavy motion. The heating of the grooved drying plates may either be effected by electric heating elements, or the drying plates 40 together with the endless belt-conveyors by means of which they are moved may be arranged within a box which is heated through hot air supplied thereto.

In accordance with a special method of carrying out the process it is also provided that the drying between the drying plates and the like does not produce a product having the commercially customary moisture content, but a moisture content of approximately 20 to 25%, because it is 45 thus much easier to cut the thread bundle in the cutting device into the desired staple length.

What is claimed is:

1. In the continuous production of staple fiber from threads of artificial origin the steps comprising wet-treating a freshly extruded bundle of threads by passing the said bundle vertically upwardly and downwardly over a plurality of rollers, wet-treating said bundle in its upward passage only under little or no tension, drying the threads, and then passing them to a cutting device.

2. In the continuous production of staple fiber from threads of artificial origin the steps comprising wet-treating a freshly extruded bundle of threads by passing the said bundle vertically upwardly and downwardly over a plurality of rollers, wet-treating said bundle in its upward passage only under little or no tension, drying the threads, curling the said threads during the 65 said drying step, and then passing them to a cutting device.

3. In the continuous production of staple fiber from threads of artificial origin the steps com-

prising wet-treating a freshly extruded bundle of threads by passing the said bundle vertically upwardly and downwardly over a plurality of rollers, wet-treating said bundle in its upward passage only under little or no tension, drying the 5 threads, curling them, and then passing them to a cutting device.

4. In the continuous production of staple fiber from threads of artificial origin the steps comprising wet-treating a freshly extruded bundle of 10 threads by passing the said bundle vertically upwardly and downwardly over a plurality of rollers, wet-treating said bundle under only the tension produced by the weight of the said bundle while being passed vertically upwardly over said 15 rollers, drying the threads, curling them, and then passing them to a cutting device.

5. In the continuous production of staple fiber from threads of artificial origin the steps comprising wet-treating a freshly extruded bundle of 20 threads by passing the said bundle vertically upwardly and downwardly over a plurality of rollers, wet-treating said bundle in its upward passage over said rollers, drying said bundle first to a moisture content of from 30 to 50%, then, 25 subsequently, drying it to a moisture content of from 20 to 25% by passing said bundle through grooved plates being rotated in the direction of travel of the thread bundle by means of an endless belt-conveyor, and prior to cutting. 30

6. In the continuous production of staple fiber from threads of artificial origin the steps comprising wet-treating a freshly extruded bundle of threads by passing the said bundle vertically upwardly and downwardly over a plurality of 35 rollers, wet-treating said bundle under only the tension produced by the weight of the said bundle while being passed vertically upwardly over said rollers, drying said bundle to a moisture content of from 30 to 50%, further drying said bundle, 40 and then passing said bundle to a cutting device.

7. In the continuous production of staple fiber from threads of artificial origin the steps comprising wet-treating a freshly extruded bundle of threads by passing the said bundle vertically 45 upwardly and downwardly over a plurality of rollers, wet-treating said bundle in its upward passage over said rollers under only the tension produced by the weight of said bundle, drying said bundle first to a moisture content of from 30 50 to 50%, then, subsequently, drying it to a moisture content of from 20 to 25% by passing said bundle through grooved plates being rotated in the direction of travel of the thread bundle by means of an endless belt-conveyor, and prior to 55 cutting.

8. In the continuous production of threads of artificial origin the steps comprising wet-treating a freshly extruded bundle of threads by passing the said bundle upwardly and downwardly over a plurality of rollers, wet-treating said bundle in its upward passage only under little or no tension, and then drying the thread.

9. In the continuous production of threads of artificial origin the steps comprising wet-treating a freshly extruded bundle of threads by passing said bundle upwardly and downwardly over a plurality of rollers, wet-treating said bundle under only the tension produced by the weight of the said bundle while being passed upwardly 65 over said rollers, and then drying said bundle.
